UNITED STATES PATENT OFFICE.

ADEA A. HOY, OF ST. LOUIS, MISSOURI.

WALL-SEAT.

1,059,467.

Specification of Letters Patent.

Patented Apr. 22, 1913.

Application filed May 19, 1911. Serial No. 628,309.

To all whom it may concern:

Be it known that I, ADEA A. Hoy, a citizen of the United States, and residing at St. Louis, in the State of Missouri, have invented 5 certain new and useful Improvements in Wall-Seats, of which the following is a specification.

This invention relates to wall-seats or the like adapted to be secured to a wall or other 10 support and constructed to be moved to extended and collapsed positions.

The objects of this invention are to construct a device of the character described which can be conveniently swung to extended 15 position to form a support or seat, and to collapsed position against the wall so as to be out of the way; to provide means for maintaining the seat in either position, and to provide a device which will be simple in 20 construction and cheap to manufacture.

The invention will be described in connection with the accompanying drawing in which:

Figure 1 is a perspective view showing 25 this invention as applied to a wall, Fig. 2 is a side elevation showing the seat extended, Fig. 3 is a side elevation showing the seat collapsed, Fig. 4 is a detail perspective view of one of the brackets, and Fig. 5 is a detail 30 showing another form of seat.

Referring to the drawing, 10, 10 designate 35 a pair of brackets which are adapted to be attached to a wall or other support, and 11 designates a guide bar or rod which is adapted 40 to be supported in these brackets. A U-shaped brace 12 is preferably constructed of a bar or rod to form an upper cross member 13 and side members or legs. The ends of the side members are bent to form bearing 45 lugs 14 which are adapted to engage suitable eyes or staples 15 secured to the floor or to the wall.

The seat or support member is of flexible 50 construction and comprises a series of slats 55 connected by one or more chains 17 located in grooves 18 cut in the lower faces of the slats. The chain links are of the same length as the slats whereby the joints will be located at the adjoining edges of the slats 60 so as to flexibly connect these slats together. The flexible support member is attached at one end to the brace by means of clips 19 secured to the forward slat and embracing the cross bar 13, and the other or rear end slat 65 is provided with hook members 20 adapted

to hook over the bar 11 mounted in the brackets.

The brackets are of novel construction. They are preferably formed of malleable metal bent to form, although they may be 60 cast if so desired. Each bracket is provided with an attaching flange 21 provided with holes to receive the fastenings for securing the brackets in position to a wall or other support. The bracket is bent to form a plurality of recesses 22 and 23 which are separated by a cam rise portion 24 providing inclined faces or shoulders. These recesses are adapted to receive the bar 11.

In assembling this device the brackets are 70 secured to the wall as shown in the drawing, and the eyes 15 are secured to the floor or wall a proper distance apart so that the legs of the brace must be sprung to position the lugs 14 in the eyes. The metal of which this 75 bar is made is resilient enough to hold the lugs in position and support the brace for swinging movement toward and from the wall. The seat or support is secured to the cross bar 13 of the brace by means of the 80 clips 19, and the hooks 21 are hooked over the bar 11 supported in the forward recesses 22 in the brackets. The seat will now be in extended position as shown in Figs. 1 and 2.

If it be desired to move it to collapsed position, it is only necessary to grasp the front slat and the cross bar 13 and swing the brace against the wall. By this movement the flexible support member or seat will be moved rearwardly, and the hooks 20 leaving 85 the bar 11, the slats will drop or roll over the bar as a guide into position against the wall as shown in Fig. 3. It will be noted that when the guide bar is in the forward recess 22 this guide bar will be spaced from 90 the wall a distance greater than the thickness of the seat member. The purpose of this is to permit free rolling movement of the slats over the guide bar 11, since a space greater than the thickness of the slats is required, due to the fact that the slats occupy an inclined position as they pass over the bar. As the brace swings against the wall, its legs will engage the guide bar and move 95 it over the rises 24 so that the bar will drop behind these rises and into the recesses 23 when the brace is moved to collapsed position. The recesses 23 are spaced from the wall at a distance approximately equal to the thickness of the slats. The guide bar 100 105 110

will therefore operate by its engagement with the recesses 23 and with the slats to latch the parts in collapsed position as shown in Fig. 3. A movement of the brace to extended position will however cause the guide bar to ride over the rises 24 and into the recesses 22 so that the seat can be readily extended, the slats riding over the guide bar and the hooks 20 automatically engaging 10 and hooking over the guide bar so as to hold the parts in extended position. The inclined faces or shoulders of the rises are sufficiently steep so as to retain the guide bar in its forward position in front of the rises when the seat is pushed back until the bar is positively moved by the engagement therewith of the brace, and to yieldingly lock the bar and seat when in locking position behind the rises. At the same time however a positive 20 force applied when collapsing and extending the seat will move the bar over the rises. It will be noted that the hooks 20 hook under and engage the guide bar as the seat is extended. These hooks not only perform 25 the function of stops to limit the extended movement of the support member, but they also prevent the end of this support member from jumping over the guide bar when the seat is quickly extended.

30 Fig. 5 shows another form of flexible seat. The slats 16 are in this case each provided with a tongue 30 and a coöperating groove 31, the lower part of the slats being cut away to form a V-cut 32 which will permit 35 movement of one slat with respect to the other. Such slats can be readily cut on ordinary wood-working machines.

It will be seen that this invention provides a seat or support which is simple and 40 durable in construction, cheap to manufacture, and easily put together in position on a wall or other support. The parts will occupy a small space when knocked down for shipment. The flexible slat seat furnishes 45 an agreeable flexible support and at the same time this support can be made sufficiently rigid so as to withstand the usage to which these devices are subjected.

Although only one embodiment has been 50 shown, it is obvious that the invention can be embodied in various forms, and can be used for a variety of purposes where it is desirable to swing a support member into and out of the way. It is further obvious 55 that various changes may be made in the details of construction without departing from this invention, and it is therefore to be understood that this invention is not to be limited to the specific construction shown 60 and described.

Having thus described the invention what is claimed is:

1. A device of the class described comprising a guide bar, a brace having means for 65 pivotally supporting the same at one end to

permit its free end to swing toward and from said guide bar, a flexible support member comprising a series of flexibly connected slats attached at one end to the free end of said brace and adapted to roll over said guide bar to extended and collapsed positions, and forwardly extending hooks on the free end of said support member adapted to engage and hook under said guide bar when the device is extended so as to limit the 70 extended position of said support member and prevent its disengagement from said bar when moved to extended position, and adapted to freely disengage from said guide bar when said device is collapsed to permit 75 said support member to roll over said guide bar to collapsed position.

2. In a device of the class described, a pair of brackets adapted to be attached to a wall, a guide bar supported in said brackets for a limited movement toward and from the wall, a swinging brace, and a flexible support member attached at one end to said brace and having means for detachably connecting it at its other end to said bar, said support member being adapted to roll over 80 said bar and move with said brace to extended position away from the wall and to collapsed position against the wall.

3. In a device of the class described, a pair of brackets adapted to be attached to a wall, a guide bar supported for movement in said bracket toward and from the wall, a swinging brace, and a flexible support member attached at one end to said brace and 90 having means for detachably connecting it at its other end to said bar, said support member being adapted to roll over said bar and move with said brace to extended and collapsed positions, said brackets being provided with recesses separated by inclined 95 portions for engaging said bar.

4. In a device of the class described, a pair of brackets adapted to be attached to a wall, a bar supported in said brackets for movement toward and from the wall, a brace, and a support member attached to said brace and said bar, said brackets being provided with rise portions forming shoulders 100 for engaging and holding said bar yielding in adjusted position.

5. In a device of the class described, a pair of brackets adapted to be attached to a wall, a bar supported in said brackets for movement toward and from the wall, a 110 brace, and a support member attached to said brace and said bar, said brackets being provided with rise portions forming oppositely inclined shoulders, said bar being adapted to ride over said shoulders from one 120 side to the other side of said rises when the device is extended and collapsed, for the purpose set forth.

6. In a device of the class described, a pair of brackets adapted to be attached to 125

a wall, a bar supported in said brackets for movement toward and from the wall, a brace, and a support member comprising a series of flexibly connected slats connected at one end to said brace and adapted to roll over said bar, said brackets being provided with shoulders spaced from the wall a distance approximately equal to the thickness of said support member, said bar being mov-

able in said brackets toward and from the wall and behind said shoulders, for the purpose set forth.

In testimony whereof I affix my signature in presence of two witnesses.

ADEA A. HOY.
